ABSTRACT

A connection network having blocking which is formed like a perfect linked system including a first switching stage consisting of a certain number of buffer storages with their addressing and reading systems, as well as a second switching stage consisting of gates associated with a certain number of distributors, the two switching stages being connected together by links and each distributor being accessible by only one link connecting it to the first switching stage, whereas a certain number of links are reserved for reciprocal overthrow.

**HIGH-CAPACITY CONNECTING NETWORK HAVING
BLOCKING CHARACTERISTICS FOR TIME-DIVISION
SWITCHING**

BACKGROUND OF THE INVENTION

1. Field of the Invention

The present invention relates to a high-capacity connecting network having blocking characteristics for time-division switching which may be employed notably in a four-wire switching center.

2. Description of the Prior Art

An unblocked connecting network is already known from French Pat. No. 1,511,678 of the 23rd Dec., 1966 in the name of the applicants which corresponds to U.S. application Ser. No. 692,144 filed Dec. 20, 1967, now abandoned, but although the construction of such an unblocked connecting network is perfectly practicable in the case of small capacities, it encounters difficulties in the case of a high-capacity network. The most important of these difficulties is due to the fact that the various items of information or words corresponding to the incoming time-division channels must be readable from a common buffer memory during a common secondary time-division channel along N_1 junction lines addressed by N_1 address lines. When the words of incoming lines are routed along a junction line towards N_2 outgoing lines having each P channels or primary channels, it is necessary that during the time of a primary channel a junction line route N_2 words, and it is said that, on a junction line, a primary channel is divided into N_2 secondary time-division channels, an incoming or outgoing line is called a primary multiplex, and a junction line is called a secondary multiplex. Two ways of constructing such an unblocked network are known:

1. Commercial memory blocks are used, which generally speaking, have only one addressing and reading circuit. In order to achieve the proposed object, it is necessary to multiply by N_1 the number of memory blocks strictly necessary. Each junction line then possesses its own buffer memory block in which all the incoming NP time-division channels are written.

2. Elemental memory points are used to which it is desirable to add individual addressing circuits and reading gates in the direction of each junction line.

These two possible forms of high-capacity unblocked connecting networks involve a superabundance of members and are consequently costly in the present state of the art.

SUMMARY OF THE INVENTION

The invention has for its object to obviate these disadvantages by providing a high-capacity connecting network having blocking characteristics.

As in conventional switching, the object in view is confined to creating a connecting network having internal blocking characteristics, i.e., one in which a certain probability of loss of communications is tolerated, which makes it possible to combine a grade of service which is considered sufficient with reasonable cost.

It is known that, in time-division switching, the connecting network has the object of routing along N outgoing network lines each having P time-division channels the intelligences contained in N incoming network lines having P time-division channels, it being understood that, in general, the intelligences contained in the p th time-division channel of the n th incoming network line may be routed along the p 'th time-division channel of the n 'th outgoing line, p, n, p' and n' having any values and it being possible for all the NP incoming time-division channels to be routed along the NP outgoing time-division channels.

The connecting network according to the invention is characterized in that during a common secondary time-division channel only a word contained in a network line and stored in a buffer memory can be read, along one junction line.

In accordance with one feature of this invention, the connecting network is in the form of a perfect linked system comprising a first junction group stage consisting of buffer memories with their addressing and reading system, and a second junction group stage consisting of gates, the two junction group stages being connected by links, and each second junction group being accessible only through a link emanating from a first junction group.

In accordance with another feature of this invention, there is employed as buffer memory a memory block comprising a single addressing and reading circuit, which can store the words preferably contained in the 16 time-division channels of an incoming network line, which corresponds to one-half of a line multiplex or primary multiplex, each word being composed of Q bits.

In accordance with another feature of the invention, the address lines coming from the control memories are subdivided into memory address lines (LAM), in which there is situated, for each secondary time-division channel, the address (one out of N) of the buffer memory from which the information is to be taken, and into word address lines (LAP) in which there is situated the address of the word of the buffer memory (one out of 16).

In accordance with another feature of this invention, the words addresses are regrouped at the level of the buffer memories in intermediate point address lines (LAPI) so that, for example, there arrive at the buffer memory n the address line (LAPI_n) in which there is found, for a given time-division channel, the address of a word which was situated in any one of the control memories with the address n of the buffer memory under consideration.

In accordance with another feature of the invention, there are present at the output of the index buffer memory n , in the intermediate junction line (LJI_n), the Q bits contained in the corresponding memory word, these Q bits being routed along the appropriate junction line by means of the decoded memory address.

In accordance with one embodiment of the invention, the connecting system consists essentially of:

1. N buffer memories, one per incoming network line, each having P memory words, one per time-division channel, which are themselves composed of Q elemental memory bits, in which there are temporarily stored the $P \times N$ words contained in the N incoming network lines;

2. N_1 junction lines, in each of which there are time-multiplexed the $P \times N_2$ words intended for a group of N_2 outgoing network lines ($N_1 N_2 \geq N$);

3. N_1 control memories, each of which contains the addresses of the buffer memory and of that work of this buffer memory at which it is necessary to seek the Q bits intended for each of the time-division channels of the N_2 outgoing network lines of the group served by a junction line associated with a control memory;

4. N_1 distributors which route from the junction lines the words intended for the N_2 network lines of the group;

5. N_1 word address lines and N_1 memory address lines, of each control memory emanating from a word address line and a memory address line;

6. N_1 decoders for distributing the memory addresses among the N buffer memories;

7. $N_1 \times N$ AND gates for distributing the digit p among the N buffer memories from the N_1 control memories;

8. N OR gates for distributing a single digit p to a buffer memory at a given instant;

10. N intermediate junction lines LJI extending from the buffer memories for distributing among the various junction lines the Q bits contained in the buffer memory word of address p ;

11. $N_1 \times N$ AND gates opening up to the aforesaid Q bits of the intermediate junction line the path of the junction line corresponding to the control memory in which the word p was stored; and

12. N OR gates for regrouping along the junction lines the words emanating from the various buffer memories.

BRIEF DESCRIPTION OF THE DRAWINGS

Further features and advantages of this invention will become apparent in the course of the detailed description given in the following with reference to the drawings, in which:

FIG. 1 illustrates a primary multiplex;

FIG. 2 illustrates a secondary multiplex both along the address lines and along the junction lines;

FIG. 3 diagrammatically illustrates a time-division connecting network according to the invention;

FIG. 4 illustrates by way of example a four-wire connection at the switching center on the calling side and the called side;

FIG. 5 is a space-division representation, conforming to conventional switching, of a time-division connecting network according to the invention; and

FIG. 6 is an exemplary space-division representation of the reciprocal overthrow.

DESCRIPTION OF THE PREFERRED EMBODIMENT

The primary multiplex illustrated in FIG. 1 is applied to an incoming or an outgoing network line which comprises 32 primary time-division channels numbered $t_1, t_2, \dots, t_k, t_p, \dots, t_{32}$. The repetition period P_R is the inverse of the sampling frequency the latter being i kc./s., the duration of the cycle is therefore 125 microseconds and the duration of a time-division channel t_p about 3.9 microseconds.

The secondary multiplex illustrated in FIG. 2 is applied to the memory and word address lines, to the junction lines and to the intermediate junction lines. This primary time-division channel is itself divided into 32 secondary time-division channels number $t_{s0}, t_{s1}, t_{s2}, \dots, t_{s31}$. One of these secondary time-division channels t_{s0} is being reserved for the writing in the buffer memory, the others being reserved for the reading of the buffer memories intended for the junction lines.

FIG. 3 shows another form of a connecting network according to the invention. It comprises N incoming network lines denoted by $LRE_1, LRE_2, \dots, LRE_n, \dots, LRE_N$. Each incoming network line corresponds for example to one-half of a primary multiplex and therefore comprises 16 primary time-division channels. There corresponds to each incoming network line one buffer memory: MT_1 to $LRE_n, \dots, MT_N$ to LRE_1 . Each buffer memory consists of a commercially obtainable memory block having a single addressing and reading circuit, in which there may be stored the words contained in 16 time-division channels. In fact, since the words are encoded in binary form with seven wires, each memory block comprises seven memories (one to each wire) and each memory comprises 16 words corresponding to the 16 time-division channels.

It may be noted that the incoming network line as here defined need not really exist; it is then regarded as a simple means of representation. For example, a primary multiplex composed of 32 time-division channels which is to be written into two buffer memories of 16 channels may be integrally presented to the input of these buffer memories. Only the writing address lines which have not hitherto been referred to, either here or in the earlier patent, permit of defining that part of the primary multiplex which is written into one or other of the buffer memories.

The network also comprises N control memories denoted by $MC_1, MC_2, \dots, MC_{n1}, \dots, MC_N$. Associated with each control memory are a junction line and a distributor giving access to a group of outgoing network lines. Thus, there are associated with the control memory MC_1 the junction line LJ_1 and the distributor CR_1 giving access to N_2 outgoing network lines from LRS_1 to LRS_2 , with the control memory MC_{n1} , the junction line LJ_{n1} and the distributor CR_{n1} giving access to N_2 other outgoing network lines $LRS_{(n-1)N_2+1}$ to $LRS_{nN_2}, \dots$, etc. Each control memory writes, under the action of external control means not shown in the diagram and for each channel of the N_2 outgoing lines of the distributor associated to a control memory by a junction line, the addresses of the buffer memory and of that word of this buffer memory at which it is necessary to seek the Q bits intended for a channel of the said

N_2 outgoing network lines. Each control memory can therefore write the addresses of any time-division channel of any incoming network line, provided however that the said control memory serves the outgoing network line of which a time-division channel p' must be brought into relationship with the time-division channel p of the incoming network line, p and p' having any values. From each control memory there emanates a word address line and a memory address line. Thus, there emanate from the control memory MC_1 the word address line LAP_1 and the memory address line $LAM_1, \dots$, from the control memory MC_{n1} there emanate the word address line LAP_{n1} and the memory address line $LAM_{n1}, \dots$, etc. On a memory address line, there is found for each secondary time-division channel, the address (one out of N) of the buffer memory from which the information is to be taken, and on a word address line there is found, for each secondary time-division channel, the address of that word of the buffer memory (one out of 16) from which the information will be taken. If the information in the control memories is encoded in binary form, each word address line will therefore comprise four wires, while each memory address line will comprise a number of wires K such that $2^K \geq N$, K being the smallest integer satisfying the inequality. The rate of flow of information along each address line wire is $32 \times 31 \times 8,000$ bits/sec. = 8,192,000 bits/sec.

Each memory address line, such as LAM_1 , for example, is connected to a decoder such as D_1 which has the object of distributing the AND gate opening signals concerning the various buffer memories. Hence, the connection 1 of D_1 collects the signal for opening the two AND-gates E_1^1, E_{a1}^1 , concerning the buffer memory MT_1 , the connection n of D_1 collects the signal for opening the two AND-gates E_n^1, E_{a1}^n , concerning the buffer memory MT_n , the connection N of D_1 collects the signal for opening the two AND-gates E_N^1, E_{a1}^N concerning the buffer memory MT_n .

Each word address line, such as LAP_1 extracts the word addresses (one to 16) concerning any one of the buffer memories MT_1 to MT_N . An AND gate of which one input is allotted to the word address line and another input to the above-defined opening signal therefore permits of allotting the word address line to the buffer memory concerned. Therefore, N_1 word address gates E are found for each buffer memory. Thus, for the buffer memory MT_1 , there is the gate E_1^1 relative to MC_{n1} , the gate E_1^{n1} relative to $MC_{N1}, \dots$, the gate E_1^{N1} relative to MC_N . The outputs of these various AND gates are applied to the input of the gate O_1 which is an OR gate. There is found at the output of this gate O_1 which constitutes the intermediate address line $LAPI_1$ the word address which was present at LAP_1 . This digit is the only one which is found at $LAPI_1$ in a secondary time division channel t_{s1} of a primary time division channel tp_1 , because when the addresses are written in the control memory, it is arranged that this is so, whereby, in addition, the blocking is introduced. An analogous formation is found for each of the buffer memories. Generally speaking, there arrives at the buffer memory MT_n the intermediate word address line $LAPI_n$, in which there is found for a given time-division channel the word address which was present in any one of the control memories with the address n of the buffer memory under consideration. It has already been noted that each word address line is in fact composed of four wires. Consequently, each gate E and each gate O will be composed of four gates, one at each wire.

The reading output of each buffer memory MT_1, MT_n, MT_N is called the intermediate junction line LJI_1, LJI_n, LJI_N . Each intermediate junction line has as many time-division channels as the address lines and is in addition composed of seven wires in the same way as the network lines. Therefore, there are found in the secondary time-division channel concerned of the intermediate junction line the Q bits contained in the buffer memory word p previously sought.

The routing of these Q bits to the appropriate junction line is effected by means of the previously defined AND gate opening signal.

Thus, referring again to the example of the time-division channel p in the network line LRE_1 to be brought into relationship with the time division channel p' of the outgoing network line LRS_K served by the control memory MC_1 , there are read from an intermediate junction line LJ_1 the Q bits contained in the word p of the buffer memory MT_1 , which Q bits were contained in the word p of the buffer memory MT_1 and were previously contained in the primary time-division channel p of the network line LRE_1 . The output 1 of the decoder D_1 opens the AND gate denoted by E_{al}^1 and there are found through this gate and the OR gate denoted by Oal , in the junction line LJ_1 , the Q bits contained in the word p of the buffer memory MT_1 . Assuming that the outgoing network line is LRS_K and the secondary time division channel tsk , the distributor CR_1 connects LJ_1 to LRS_K at the instant tp'/tsk and there are found in the channel p' of the outgoing network line KRS_K the Q bits contained in the channel p of the incoming network line LRE_1 .

Each intermediate junction line is capable of distributing Q bits by word to any one of the groups of outgoing network lines, i.e., to any one of the junction lines. Thus, the intermediate junction line LJ_1 distributes its items of information among $LJ_1, \dots, LJ_{al}, \dots, LJ_{N1}$, respectively through the AND gates denoted by $E_{al}^1, \dots, E_{al}^1, \dots, E_{al}^1$; and the intermediate junction LJ_{N1} distributes its items of information among $LJ_1, \dots, LJ_{al}, \dots, LJ_{N1}$, respectively through the AND gates denoted by $E_{al}^2, \dots, E_{al}^2, \dots, E_{al}^2$, etc. There are therefore $N_1 \times N$ AND gates allocated to the intermediate junction lines. At the output, there are N_1 OR gates denoted by $Oa1, Oa2, \dots, OaN1$; there corresponds to each of these OR gates a group of N_2 outgoing network lines ($N_2=32$ and corresponds to the secondary multiplex of an intermediate junction line). Each group of N_2 outgoing network lines is served by a junction line and a distributor. Hence, the first group of outgoing lines $LRS_1, LRS_2, \dots, LRS_K, \dots, LRS_{N2}$ is served by the junction line LJ_1 and the distributor $CR_1, \dots$ etc., and likewise for each group.

By way of practical example, the aforesaid device operates as follows. In a four-wire switching center $CC4$ (FIG. 4), there is obviously one outgoing two-wire channel and one return two-wire channel. Within the switching center, the outgoing channel and the return channel may be dissociated in order to facilitate the switching. For example, it will be assumed that the outgoing channel of the network line leads to the buffer memory MT_1 and that the return channel of the network line leads to the buffer memory MT_9 .

With regard to the outgoing channel, it will be assumed that it is desired to find in the outgoing network line LRS_2 in the time-division channel 19 the Q bits contained in the time-division channel 15 of the incoming network line LRE_1 .

With regard to the return channel, it will be assumed that it is desired to find in LRS_{35} , in the time-division channel 28, the Q bits contained in the time-division channel 8 of the incoming network line LRE_9 .

It will first of all be seen what happens in the outgoing direction, i.e., the direction from the caller to the called subscriber.

The outgoing network lines LRS_2 is the second of the first group. There will therefore be found at the output of the control memory MC_1 , at the instant $tp19/ts2$ at the memory address line LAM_1 , the digit 1 (corresponding to MT_1) and at the word address line LAP_1 the digit 15 (15th primary time-division channel). The output 1 at the decoder D_1 opens the AND gate denoted by E_1^1 and there is found through this gate and the OR gate denoted by O_1 at the intermediate word address line LAP_1 the digit 15, which was present at LAP_1 . This digit is the only one which is found at LAP_1 at the instant $tp19/ts2$, whereby the blocking is introduced. Within the buffer memory MT_1 , the word 15 at LAP_1 initiates the reading at the intermediate junction line LJ_1 of the Q bits contained in the word 15 of this buffer memory, which Q bits were previously contained in the primary time-division channel 15 of the incoming network line LRE_1 . The output 1 of the decoder D_1

opens the AND gate denoted by E_{al}^1 and there are found through this gate and the OR gate denoted by Oal at the junction line LJ_1 the Q bits contained in the word 15 of the buffer memory MT_1 .

5 During this instant $tp19/ts2$, the distributor CR_1 is connected to the outgoing network line LRS_2 and there are in fact found in the channel 19 of the outgoing network live 2 of the first group the Q bits contained in the channel 15 of the incoming network line LRE_1 .

10 Exactly the same thing happens in the return direction, i.e., in the direction from the called subscriber to the calling subscriber.

The outgoing network lines LRS_{35} is the third one of the second group, since each group of outgoing network lines comprises 32. There will therefore be found at the output of the control memory MC_2 at the instant $tp28/ts3$ in the memory address line LAM_2 the digit 9 (corresponding to MT_9) and in the word address line LAP_2 the digit 8 (eighth primary time-division channel).

15 The output 9 of the decoder D_2 opens the AND gate denoted by E_9^2 and there is found through this OR gate denoted by O_9 in the intermediate word address line LAP_9 the digit 8 which was present at LAP_2 . This digit is the only one which is found at LAP_9 at the instant $tp28/ts3$.

20 25 whereby the blocking is introduced. Within the buffer memory MT_9 , the digit 8 at LAP_9 initiates the reading at the intermediate junction line LJ_9 of the Q bits contained in word 8 of this buffer memory, which Q bits were previously contained in the primary time-division channel 8 of the incoming network line LRE_9 . The output 9 of the decoder D_2 opens the AND gate denoted by E_{a2}^9 and there are found through this gate and the OR gate denoted by $Oa2$ in the junction line LJ_2 the Q bits contained in the word 8 of the buffer memory MT_9 . During this instant $tp28/ts3$, the distributor CR_2 is connected to the outgoing network line LRS_{35} and there are in fact found in the channel 28 of the outgoing network line 3 of the second group the Q bits contained in the channel 8 of the incoming network line LRE_9 .

30 35 The line numbers indicated above are obviously chosen only by way of example. As a general rule, there is a very close correlation in the numbering of the two transmission directions. Thus, as in carrier-current systems, the channel of the PCM systems will be numbered in the same way in both

40 45 directions of transmission. Thus, the circuit 24 of the multiplex numbered 2 in a central office is found, for both directions of transmission, in the time-division channel 24 of the multiplex. In the central office, on the outgoing side, the multiplexes correspond to the outgoing network lines. The Q bits concerning this circuit are therefore to be found in the time-division channel 24 of the network line 2. On the incoming side, the multiplexes are subdivided into two incoming network lines in the example chosen. Thus, the multiplex 1 is subdivided in such manner that its odd channels are found in the incoming network line 1 and its even channels in the incoming network line 2. Therefore, the incoming side of the circuit 24 of the multiplex 2 will again be found in the time-division channel 12 of the line.

50 55 60 FIG. 5 illustrates the space-division equivalent of the time-division connecting network according to the invention which has been described with reference to FIG. 3. It will be seen that it is a question of a perfect linked system employed in conventional switching. Such linked systems have, due to their very construction, a slight defect in the accessibility of the incoming lines to the outgoing lines, because, although there always exists one link by which any incoming line can be connected to any outgoing line, it may happen at certain times that no free outgoing line can be reached from a given incoming line, simply because the link or links which enable it to reach the free outgoing lines are all occupied. It is then said that there is internal blocking.

65 70 75 In the transposition from time-division to space-division as illustrated in FIG. 5, a first type of switch CT consists of the buffer memories with their addressing and reading system.

There arrive along an incoming network line 16 primary time-division channels, and in an intermediate junction line allocated to this network line there are found $32 \times 32 = 1,024$ secondary time-division channels. This is represented by a switch CT_1 having 16 inputs VE_1^1 to VE_1^{16} , of which the 1,024 links M_1^1 to $M_1^{1,024}$ are the outputs. There are therefore as many switches CT as there are incoming network lines. If there are N network lines, the last switch is CT_N , the inputs of which are numbered VE_N^1 to VE_N^{16} . The set of switches CT_1 to CT_N constitute the first stage of the connecting network.

The second stage of the connecting network consists of the AND and OR gates which regroup at the junction lines the items of information carried by the intermediate junction lines. A switch such as CS_1 receives a link emanating from each network line CT_1 to CT_N , since, for each junction line, there is only one connection with a network line during a secondary time-division channel. This connection is taken from the wires 1 to N ; the number of outputs of CS_1 is given by the number N_1 of junction lines, each junction line being independent of the others.

It is therefore a stage of which each switch has N inputs and N_1 outputs. There are 1,024 switches CS to take account of the fact that, during a sampling period, the network of gates, of which there is only one, occupies 1,024 successive positions during the 1,024 secondary time-division channels. It is a question of a perfect linked system, each secondary junction group being accessible by a single link emanating from a primary junction group CT .

FIG. 6 shows by way of example a diagram illustrating on a space-division basis, a connecting network having blocking characteristics and reciprocal overthrow for 4,000 network lines.

It is known to obviate the internal blocking of a network by reciprocal overthrow in such manner that it does not ultimately and systematically result in a loss of communication. The reciprocal overthrow performs the following function. If the call cannot be serviced from the original primary junction group, i.e., from the junction group in which it arises, it is then sent back to another primary junction group of the input stage which is capable of servicing the call effectively. Thus, when a blocked condition exists, the reciprocal overthrow device reintroduces a call at the input in order that it may be successfully completed. It therefore follows that the traffic offered to the reciprocal overthrow is the traffic refused by the normal group without the use of the reciprocal overthrow.

The network according to the invention, as described by way of example, is composed as follows. On the incoming side E there are 256 primary junction groups, including 160 from PN_1 to PN_{160} having 16 incoming circuits R_1 to R_{16} per junction group and 96 junction groups with reciprocal overthrow PE_{161} to PE_{256} having 15 incoming circuits R_1 to R_{15} per junction group and also one reciprocal overthrow circuit per junction group.

There are therefore in all $(160 \times 16) + (96 \times 15) = 4,000$ incoming circuits and 96 reciprocal overthrow circuits.

On the outgoing side S , there are 1,000 secondary junction groups from CS_1 to $CS_{1,000}$, each of which has four outputs S_1 to S_4 , which represents 4,000 outputs. In addition, the 24 reciprocal overthrow junction groups SE_{1001} to SE_{1024} each give an outlet to four reciprocal overthrow circuits such as CE_1 to CE_4 , i.e., 96 reciprocal overthrow outlets.

Of each primary junction group PN_1 to PN_{160} and PE_{161} to PE_{256} , there are 1,000 links M_1 to $M_{1,000}$ which are distributed among the 1,000 secondary junction groups CS_1 to $CS_{1,000}$ and 24 reciprocal overthrow selectors SE_{1001} to SE_{1024} . Each secondary junction group such as CS_1 therefore receives 256 direct links coming from the incoming circuits and each reciprocal overthrow selector also receives 256 reciprocal overthrow links coming from the incoming circuits.

The reciprocal overthrow circuits CE_1 to CE_{96} emanating from the 24 reciprocal overthrow selectors SE_{1001} to SE_{1024} are introduced at the input in a proportion of one reciprocal overthrow circuit such as CE_1 per primary mixed junction group such as PE_{161} .

It will be assumed by way of example that a call at the primary junction group PN_1 is to be routed to the outlet S_1 emanating from the secondary junction group CS_1 . If the link M_1 which connects PN_1 to CS_1 is already occupied by another call, blocking occurs and it is necessary to find another channel. A free link is chosen from the reciprocal overthrow links accessible from the primary section PN_1 in which the call is engaged. It will be assumed by way of example that this is the link ME_{24} . The link ME_{24} is in addition that one which possesses a reciprocal overthrow selector SE_{1024} giving access to a mixed primary junction group having a free link M_1 towards the secondary junction group CS_1 , of which one outlet is the desired direction S_1 .

The transposition of the reciprocal overthrow (which has just been described with reference to FIG. 6 in the case of space-division switching) to time-division switching takes place without difficulty (see FIG. 3).

The chain line ENT (FIG. 3) represents the reciprocal overthrow in time-division switching. It comprises, for the network taken by way of example, 96 outlets (CE_1 to CE_{96} , FIG. 6) taken from the junction lines in a proportion of 24 secondary channels per junction line. The secondary channels are repositioned at the input of the network lines, for example, as indicated in FIG. 6, as the 16th input of the primary junction groups from PE_{161} to PE_{256} .

The distribution given for the reciprocal overthrow circuits among the primary junction groups and the secondary junction groups has been chosen by way of example. It is equally possible to take only one reciprocal overthrow circuit per secondary junction group and there are then 96 mixed secondary junction groups. Likewise, all the reciprocal overthrow circuits may be returned to specialized primary junction groups and there are then 6 specialized primary junction groups. This method is easier to put into practice.

Of course, the invention is in no way limited to the embodiment described and illustrated, which has been referred to only by way of example. More particularly, details may be modified, certain arrangements may be changed and certain means may be replaced by equivalent means without departing from the scope of the invention.

What is claimed is:

1. A high-capacity connecting network in the form of a linking system for time-division switching having blocking and reciprocal overthrow characteristics comprising:
  - a. a plurality of incoming network lines;
  - b. a plurality of buffer memories each of said buffer memories corresponding to one of said incoming network lines;
  - c. a plurality of junction lines associated with said buffer memories;
  - d. a plurality of control memories, each of said control memories corresponding to one of said junction lines;
  - e. a plurality of groups of outgoing network lines;
  - f. a plurality of intermediate junction lines, each of said intermediate junction lines corresponding to one of said buffer memories, wherein each of said buffer memories is capable of storing the items of information or words contained in 16 primary time division channels, each primary time division channel being multiplexed into 32 secondary time-division channels on said intermediate junction line;
  - g. word address lines and memory address lines associated with each of said control memories, wherein said memory address line carries the address of the buffer memory from which the information is to be taken for each secondary time-division channel and wherein said word address line carries the address of the word in that buffer memory and wherein the memory address lines and word address lines are connected to said buffer memories through a logic circuit, said logic circuit comprising:
    1. a plurality of first AND gates, each first AND gate having one input connected to one word address line and another input connected to a decoder means;
    2. a plurality of first OR gates, each first OR gate associated with one of said buffer memories wherein the

- outputs of said first AND gates are applied to the inputs of said first OR gates, whereby one of said first AND gates and one of said first OR gates are simultaneously opened during a common secondary time-division channel;
- h. said decoder means being associated with each of said memory address lines whereby the output of said control memories is applied to said word address lines and said memory address lines, such that the items of information stored in one of said primary time-division channels of a buffer memory is applied to the corresponding intermediate junction line and wherein the signal on said intermediate junction line is applied to an appropriate outgoing network line; and
- i. a plurality of distributor means, each said distributor means connected to one junction line and one group of outgoing network lines, wherein words received on one of said network lines and stored in one of said buffer memories cannot be read from two of said junction lines on a common secondary time-division channel.
2. A connecting network according to claim 1, wherein said intermediate junction lines are connected to one input of a group of second AND gates, the other input of said group of second AND gates being connected to one of the outputs of said decoders, the outputs of said group of second AND gates being connected to one input of a second OR gate, the output of which constitutes a junction line, whereby said second OR gate and one of said second AND gates are simultaneously opened during a common secondary time-division channel.
3. The connecting network according to claim 2, wherein each junction line comprises a number of secondary time-division channels and wherein a number of said secondary time-division channels and line are allotted to the reciprocal overthrow and reintroduced at the input of a certain number of network lines such that a new access channel towards the desired outgoing network lines can be found if there is internal blocking of the network.
4. A connecting network according to claim 2 which comprises:
- a. N of said buffer memories, one per incoming line, each 40

- having P memories, one per time-division channel, which are themselves composed of Q elemental memory bits, in which there are temporarily stored the $P \times N$ words contained in the N incoming network lines;
- b. N_1 of said junction lines, in each of which there are time-multiplexed the $P \times N_2$ words intended for a group of N_2 outgoing network lines ($N_1 N_2 \geq N$);
- c. N_1 of said control memories, each of which contains the addresses of the buffer memory and of that word of this buffer memory at which it is necessary to seek the Q bits intended for each of the time-division channels of the N_2 outgoing network lines of the group served by a junction line associated with a control memory;
- d. N_1 of said distributor means which route from the junction lines the words intended for the N_2 network lines of the group;
- e. N_1 of said word address lines and N_1 memory address lines of each control memory which emanate from a word address line and a memory address line;
- f. N_1 of said decoders for distributing the memory addresses among the N buffer memories;
- g. $N_1 \times N$ of said first AND gates for distributing the digit P among the N buffer memories from the N_1 control memories;
- h. N of said first OR gates for distributing a single digit P to a buffer memory at a given instant;
- i. N of said intermediate word address lines between the first OR gates and the buffer memories;
- j. N of said intermediate junction lines coming from the buffer memories for distributing among the various junction lines the Q bits contained in the buffer memory word of address p;
- k. $N_1 \times N$ of said second AND gates opening to the aforesaid Q bits of information of the intermediate junction line, the path of the junction line corresponding to the control memory in which the digit p was stored;
- l. N_1 of said second OR gates effecting the regrouping in the junction lines of the items of information coming from the various buffer memories.
